DESIGN FOR A HIGHWAY TRAFFIC MARKER

Leslie M. Wise, McKeesport, Pa., assignor of
one-half to William L. Kann, Pittsburgh, Pa.

Application December 12, 1938, Serial No. 81,714

Term of patent 14 years

To all whom it may concern:

Be it known that I, Leslie M. Wise, a citizen
of the United States, residing at McKeesport,
in the county of Allegheny and State of Penn-
sylvania, have invented a new, original, and orna-
mental Design for a Highway Traffic Marker,
of which the following is a specification, refer-
ence being had to the accompanying drawing,
forming a part thereof.

In the drawing Fig. 1 is a plan view of a high-
way traffic marker showing my new design; Fig. 2
is a side view thereof; and Fig. 3 is a side view
of the marker turned 90° from the view shown
in Fig. 2.

I claim:

The ornamental design for a highway traffic
marker, substantially as shown.

LESLIE M. WISE.
